APPARATUS FOR APPLYING GLAZE

Benjamin A. Jeffery, Clarkston, Mich., assignor,
by mesne assignments, to Champion Spark Plug Company,
Toledo, Ohio, a corporation of Delaware (1938)

Application May 12, 1937, Serial No. 142,316

5 Claims. (Cl. 91—43)

This invention relates to an apparatus for applying glaze or similar coating material to spark plug cores or other forms of circular cross-section.

The purpose of the invention is to devise an apparatus whereby glaze or similar coating liquids may be applied to a spark plug core or other form of circular cross-section in quantity both as to thickness and extent exactly as desired and without waste of the glaze.

10 A further object is to provide an apparatus whereby the article to be coated can be buffed or smoothed in certain sections where desired before the application of glaze to other sections, and without extra handling.

15 Another object is to provide means by which the surface of the object may be brushed.

Another object is to provide means whereby a central bore in the object may be chamfered at one end, if desired, without requiring additional 20 handling of the object.

A further object of the invention is to provide an apparatus by which the buffing and application of glaze can be combined in the same apparatus without contaminating the glaze with particles removed from the articles in the buffing or other operations.

Further objects and details of the invention will appear as the description proceeds.

In the accompanying drawings forming a part 30 of this specification,

Figure 1 is a front elevation, partly diagrammatic, disclosing one embodiment of the invention;

Fig. 2 is a side view, partly in section and partly 35 broken away, illustrating the apparatus shown in Fig. 1;

Fig. 3 is a partial elevation of the apparatus shown in Fig. 2, showing a slightly different arrangement of pulleys;

40 Fig. 4 is an enlarged detail showing the application of glaze by the apparatus indicated in Fig. 2 and also showing a supplemental device not shown in Fig. 2;

Fig. 5 is an enlarged view of the glaze-applying 45 device, partly in section, viewed from the front;

Fig. 6 is a section through one of the cores in the buffing position.

The apparatus disclosed is mounted upon a main frame column 8 on which there is mounted 50 a bracket 9 carrying a motor 10 which drives the gearing in a gear reducing box 11 and thereby operates main shaft 12 at a relatively slow speed. On one end of shaft 12 there is a pulley 13, while on the other end of the shaft there are pulleys 55 14, 15 and 16. A pulley 17 is connected by a

suitable belt drive 18 with pulley 13 and drives a shaft 19 which drives the gearing in a gear box 20 to operate a paddle, not shown, in glaze tank 21.

A pulley 25 is driven by a belt, indicated diagrammatically at 26, from pulley 14 on shaft 12. Pulley 25 is fixed on shaft 27 which extends into and drives a glaze roller 28 in the glaze fountain 29. A bracket 30 extending from the main column 8 supports a plate 31 on which the glaze tank 10 and shaft 27 are suitably mounted. Plate 31 may 15 be adjusted longitudinally of shaft 27 by means of screws 32 and may be adjusted vertically by means of screw 33, screws 32 acting as a hinge support for the plate 31.

A belt indicated diagrammatically at 35 connects pulley 15 with a pulley 36 on a shaft 37 which drives the gearing in a box 38 and through this gearing drives a pulley 39 which in turn drives a belt indicated diagrammatically at 40. This belt is suitably tightened by an idler wheel 20 41, and drives a turntable 42 which carries a plurality of spindles 43.

There is diagrammatically indicated at 44 a belt driven by pulley 16 and tightened by idler 25 tension wheels 45 and passing around the pulleys 46 which drive the several spindles 43.

A bell crank lever 50 is operated by a cam 51 located in a groove 52 on the hub 53 of turntable 42. The lever operates a valve rod 54 which in 30 turns operates a valve, not shown, in glaze tank 21, which permits glaze to flow through inlet 55 into a glaze fountain 29. The glaze fountain is provided with an overflow 56 from which excess glaze flows from the fountain into an overflow tank 57.

A pulley 58 is mounted on shaft 19 beside pulley 17 and drives a pulley 59, connected through suitable gearing to an agitator in the overflow tank 57, by a suitable belt 59'.

As the glaze roller 28 rotates, it lifts a film 60 40 of glaze from the fountain and brings it up into contact with a baffle pin 61 mounted parallel with and in close juxtaposition to the upper surface of the glaze roller. The baffle pin is arranged at the proper distance from the surface of the glaze 45 roller so as to provide a pool 62 of glaze of exactly the height desired. In order to adjust the pin, it is mounted in a pin holder 63 which in turn is projected from an adjusting table 64. A screw 65 may be employed to adjust the pin holder longitudinally and screws 66 and 67 may be used to tilt the table as desired. Guards, guides or vanes 68 and 69 are provided in close juxtaposition to the pin so as to limit the width of the pool 62.

In Fig. 4, there is indicated also a supplemental glaze fountain 78 having therein a glaze roller 71, which may be driven by any suitable means, and a baffle pin 72 provided with guards 73. Preferably the supplemental fountain is an independent unit with its roller separately driven, but where desired the shaft 27 may be continued and roller 71 mounted thereon and, if desired, the two rollers might operate in the same fountain instead of in separate fountains. Where shaft 27 passes through the wall of the glaze fountain, a suitable sealing device or stuffing box is provided to prevent leakage.

Where it is desired to buff the articles as well as apply glaze thereto, buffing apparatus may be mounted adjacent the path of the spindles before they reach the glaze fountains. In the drawings, there is shown for this purpose two strips of felt 74 and 75 mounted in holders 76 (see Figs. 6, 20 1, and 2). The holders 76 are mounted, adjustably upon a bracket 77 which is in turn adjustably mounted on a support 78. The lower ends of holders 76 may be adjusted to and from the path of the spindles by means of screws 79 having rubber tips which provide a somewhat yielding pressure. Other adjustments of the felt strips may be made as desired, as will be clear from the construction illustrated without further description.

Projecting from each spindle 43 there is a pin 80 and a socket 81 upon which there may be mounted a spark plug core 82 or similar device which is to be coated. In the form of plug shown, a shoulder 82A is provided for mounting 35 in a shell in a well known manner. The two sides of the shoulder 83 and 84 are contacted by the felts 74 and 75, respectively, so that they are brushed smooth during their movement past these felts. This smooths the sides of the shoulder which contact the packing rings by which the shoulder is mounted in the shell. In the form illustrated, there is shown a fan 86, operated by motor 10, which may be connected in any suitable manner to a shielding guard 87 40 which is mounted in position to catch any air-suspended dust released by the operation of buffing felts 74 and 75 and avoid contamination of the glaze fountain by such dust. The fan also draws away any objectionable vapor from the glaze-suspending medium.

In the form of apparatus illustrated, turntable 42 is attached by bolts 90 to its hub 53, which is in the form of a sleeve rotating about a fixed shaft 91. If desired, a holder 92 for a brush 93 may be attached to shaft 91 in position to hold the brush in contact with the cores and brush any loose particles therefrom while they are being buffed. If desired, holder 92 may be formed, as shown in Fig. 2, with flanges 94, so as to form a pan to catch anything that might accidentally drop from the upper portion of the turntable.

Sockets 81 are preferably of rubber or similar material which yieldingly and frictionally engages the cores when they are positioned on pins 80. A cutting member 95 may be mounted on each spindle 43 parallel with pin 80, and with its end so disposed as to chamfer the end of the central bore 96 of a core when it is first placed upon pin 80, shoved into socket 81, and held against rotation by the hand of the operator. Preferably the socket is provided with relief at 97 to provide clearance for cuttings caused by the chamfering operation.

It will be readily understood that the operator

places the cores upon pins 80, and holds them momentarily against rotation to effect the chamfering, as they approach the buffers. After the core is released by the operator, the frictional engagement of the socket, especially the thin, stretched edge 88, insures the rotation of the core as it moves between the buffing or smoothing pads and the brush, whereby it is smoothed and cleaned. It will be readily understood that the pads and brush or brushes may be arranged in any desired way to effect the desired brushing and smoothing of the surface of the core while it is passing towards the glazing tank.

After being buffed, cores are carried down to a position such as that shown in Figs. 4 and 5, where the under surface is contacted by glaze pool 82 and a similar pool which is banked up against pin 72. By adjustment of the pins and guards, the width of the pool can be adjusted so that as wide a stripe as desired will be applied to the core. Also, the height of the pins above the surfaces of the rollers 28 and 11 may be adjusted independently so as to control accurately the depth of the pool and thereby the thickness of glaze which is applied to the rotating core. In this way the surface 88 of the core between guards 88 and 89 has applied thereto the desired amount of liquid glaze. At the same time, if desired, a supplemental belt of glaze can be applied at 89 by the supplemental tank.

It will be readily understood that the arrangement of these rollers and guards is merely illustrative of the application of glaze to one particular form of spark plug core, and that various changes may be made in the number and arrangement of the glaze rollers and baffle pins and guards to apply strips of glaze as desired to different forms of circular cross-section which may be carried upon the several spindles.

After the glaze has been applied, the continued rotation of turntable 42 carries the cores on upward and the glaze is allowed to dry during the continued rotation of the core for the desired length of time, and the core may be removed in time to supply the spindle with an untreated core before the buffing strips are again reached.

It will be readily understood that from time to time the excess glaze in tank 57 may be returned to tank 21 so that, although the circulation described keeps the glaze fresh as presented by the fountain, the overflow is not wasted, but is returned to the supply tank.

Adjustment of the pin by means of screw 65 moves it forward or back as desired with respect to the direction of movement of the surface of roller 28. It will be readily apparent that the movement of the pin to a point somewhat to the left of the center of the roller, as viewed in Fig. 5, renders it more easy to bank up the coating liquid than would a position farther to the right. By adjustment in this way, it is possible to regulate to some extent the width of the pool in the direction of movement of the roller. The height of the pool, of course, may be governed to some extent by the vertical adjustment of the pin. By these two adjustments, the shape and size of the pool can be controlled within the necessary limits. The viscosity of the glaze suspended liquid also affects the height and width of the pool, and the thickness of the coating of glaze applied to the core is affected by the combined effects of the height of the pool, its width in the direction of movement of the core, and the specific gravity and viscosity of the applied liquid.

While baffle pin 61 has been shown as cylind-

drical, it will be understood that its contour may be modified when found desirable. Cutting away any portion of the underside of the pin obviously allows freer passage of the glaze therebeneath and lessens, or removes, its baffling effect at that point.

While the illustrated arrangement of the driving mechanism, etc., has proved convenient and effective in actual operation, it will be readily understood that various changes may be made in the apparatus, within the scope of the appended claims, without departing from the spirit of the invention.

In the appended claims the term "buffing" is employed in a broad sense to cover any brushing or smoothing operation to improve the surface by removing loose particles and/or smoothing.

What I claim is:

1. In apparatus of the character described, a carrier, spindles mounted upon the carrier and each adapted to support and rotate a ceramic article, a glaze fountain beneath the path in which the ceramic articles are moved by the carrier, a roller in the fountain having its upper surface spaced below the path of said articles and above the normal surface of the liquid in the fountain, means to rotate the roller and carry a

film of glaze on the surface thereof, and a baffle located in the path of the film and beneath the ceramic articles in position to bank up the film and form a pool that contacts the ceramic articles when in position over the roller in the fountain.

2. Apparatus in accordance with claim 1 and having guards cooperating with the baffle and limiting the width of the pool.

3. Apparatus in accordance with claim 1 and comprising means for adjusting the baffle with respect to the roller.

4. Apparatus in accordance with claim 1 and wherein the baffle is in the form of a cylindrical pin with its axis substantially parallel with that of the roller.

5. In coating apparatus, a receptacle for containing liquid, a roller in the receptacle with its upper surface above the normal level of the liquid, means to rotate the roller, a stationary baffle consisting of a cylindrical pin having its axis above and substantially parallel with that of the roller, and means for adjusting the pin with respect to the surface of the roller both in the direction of the movement of that surface and to and from that surface.

BENJAMIN A. JEFFERY.
